SHOE FLAP ATTACHABLE TO A SHOE LACE

Rosalie Ortner, 48 Elmwood Terrace,
Linden, N.J. 07036

Filed June 17, 1974, Ser. No. 479,626

Term of patent 14 years

Int. Cl. D2—04

U.S. Cl. D2—314

The single figure of the drawing is a front elevational view of a flap attachable to a shoe lace showing my new design, the flap being of conventional thickness.

I claim:

The ornamental design for a shoe flap attachable to a shoe lace, as shown and as described.
